Application April 14, 1948, Serial No. 21,022

8 Claims. (Cl. 179—171)

1 My invention relates to amplifying circuits and more particularly to a sensitive amplifier for handling minute currents and which utilizes tubes whose filaments are supplied from a single high voltage power supply with protective control circuits for preventing injury to the tubes due to voltage surges, changes, or abnormal conditions.

In the prior art it has been the general practice to supply each of the filaments of the tubes of a circuit from a low voltage heater current power source or supply. This has been particularly true of sensitive direct current voltage amplifiers employed to measure very small currents where regulator tubes are required to maintain supply voltages as nearly constant as possible. See Vance 2,190,743. In these cases performance suffers from the lack of adequate voltage regulating systems and protective devices.

Applicant with a knowledge of these problems in the prior art has for an object of his invention the provision of a voltage regulator system for the power source of an amplifier circuit which is instantaneously responsive to changes in supply voltage for maintaining the voltage output at substantially a fixed value.

Applicant has as another object of his invention the provision of an amplifier system employing tubes whose filaments are fed from the high voltage power supply source with a protective arrangement for safeguarding the filaments from injury or being burned out by variations in voltage from the power source.

Applicant has as a further object of his invention the provision of a safety device for a voltage control circuit which prevents injury to components of a system fed through the voltage control circuit upon failure of any of the elements of such circuit to properly function.

Applicant has as a still further object of his invention the provision of a negative feedback amplifier circuit employed in a system for the continuous measurement of minute currents with an A. C. operated instrument having negligible zero drift.

Applicant has as a still further object of his invention the provision of a direct current degenerative feedback voltage amplifier for feeding a sensitive milliammeter and for measuring weak currents with safeguards in the form of voltage regulating and overload control circuits to prevent injury to the elements of the system resulting from failure of components of the voltage regulating system to properly function.

Other objects and advantages of my invention will appear from the following specification and

2 accompanying drawings, and the novel features thereof will be particularly pointed out in the annexed claims.

In the drawings,

5 Fig. 1 is a schematic of a direct current negative feedback amplifier.

Figure 2 is a schematic of pre-amplifier portion of the circuit of my current measuring system.

10 Figure 3 is a schematic of another portion of the circuit of my current measuring system incorporating the improved voltage regulating and overload protective circuits.

The present apparatus, which represents the 15 preferred embodiment of the invention, was especially designed to detect and measure the extremely small currents which flow to the collecting plate in a mass spectrometer. These currents are of the order of 5×10^{-14} to 5×10^{-10} amperes.

20 Accordingly, these currents could not operate a normal voltmeter or other measuring device directly because the amperage would be far too low.

Referring particularly to Fig. 1 wherein A' designates schematically a direct current amplifier, 25 such amplifier is fed from the collector plate 13 of a mass spectrometer and is associated with input and output resistors R₁ and R₀, respectively. The output is fed back in series with the input in such a manner as to provide degeneration.

In this arrangement the voltage change is represented as follows:

$$V_c = \frac{V_s}{1+G}$$

35 In the above equation V_c is the voltage change; V_s is the input voltage or potential at the collector of the spectrometer; and G is the normal gain of the amplifier A' without considering the feedback connection. Any voltage at the input is thus matched by the output to an accuracy of:

$$\frac{1}{1+G}$$

45 If G equals 1000, then the output matches the input by one part in 1001. By making G very large, the output voltage may be made negligibly different from the input voltage. It will be seen further that if the gain G is large between the input and output, a voltage gain of substantially unity may be obtained.

The current gain, however, is only unity when R₁ = R₀, i. e., when the resistance or impedance of the input circuit equals the resistance or impedance of the output circuit. If R₁ is made many times the value of R₀, a large current amplifica-

tion may be obtained. The current gain is equal to R_i/R_o . It can be seen, therefore, that the calibration of this system depends upon the input and output impedances R_i and R_o , and that tube characteristic changes only slightly affect the accuracy in calibration. The amplifier, being a direct current amplifier, will permit a definite calibration and equilibrium condition which will resist any changes by a factor of $1+G$. This facilitates holding zero points in measuring direct currents.

A measure of the input current or voltage may be obtained by measuring the output voltage or current in connection with the output impedance R_o and its relation to the input impedance R_i , as will be seen by referring now to Fig. 2.

In Fig. 2 the collector plate of a conventional mass spectrometer is generally indicated at 13. This feeds through line 61 into the suppressor grid 15 of the first stage 16 of a preamplifier. Line 61 is also connected at 32 through input resistor 31, line 14, direct current source 49, and output resistor 30 to ground. The small shunt condenser 62 is employed for the passage of transient currents, since this low impedance to high frequencies gives a good transient response. The output circuit of tube 16 is directly coupled to the control grid 21 of the amplifier 22 at 20. The output circuit of the second stage 22 of the preamplifier in turn feeds directly into the control grid circuit of amplifier 26 at 24, and the output of amplifier 26 is directly coupled at point 27 to the control grid 28 of tube 29, which tube functions as a cathode follower to couple the direct current amplifier system, just described, back to the input circuit through the output resistor 30 and the cathode circuit of tube 29 in order to produce a negative feedback. The cathode follower is used in this arrangement to provide a low impedance current source. A milliammeter 12 and variable resistor 60 provide a circuit bridging the output resistor 30 and E. M. F. source 49 to measure the current flow.

In an instrument such as a mass spectrometer, the minimum "collector" current which can be detected and/or measured with any degree of accuracy will depend primarily upon the residual current fluctuations in the resistor 31. These currents arise due to (1) thermol currents in the resistor proper, (2) currents flowing to the grid connection due to surface leakage of the tube and mounting parts, and (3) currents flowing inside the tube 16 to the grid proper from the cathode and other elements. The last mentioned current, generally known as grid current, is the most troublesome and it is for this reason that the tube 16, preferably type 954, is connected as it is.

The voltages on the elements of the tube 16 are very low, that is, considerably lower than the ionization potential of any gas which may be present in the tube. Grids 63 and 64, which are normally the control and screen grids respectively, draw the greater part of the total current from the cathode. Due to the series resistor 65 of 2000 ohms these grids function in such a way as to stabilize electron emission which arrives at the plate from the cathode. For example, if emission tends to increase due to a change in cathode temperature, the grids, since they are drawing current, will go less positive due to the additional voltage drop across the 2000 ohm resistor. Since their potential influences the current flow to the plate, a balance or regulating condition is attained.

The third grid 15, which is normally the suppressor grid, is very little affected by the space charge electrons surrounding the cathode. However, some small quantity of electrons will strike the grid and some will leave. The tube is operated in such a way that the sum of these "positive and negative grid currents" is zero or nearly so. Inherent grid current fluctuations in this circuit are of the order of 5×10^{-15} amperes.

Considering the operation of the apparatus more in detail, it is necessary first to regulate the apparatus so that the milliammeter 12 will read zero when no current is flowing from the collector plate 13. Assuming that the milliammeter 15 reads upscale when the plate 13 is disconnected from the system, there must be a voltage drop between the point 11 and the ground. Due to the connecting line 14, this places a certain charge on the grid 15 of the first stage tube 16. Whatever the nature of this charge on the grid 15, some current will flow across the tube 16 between filament and plate and consequently will flow through the resistance 17.

As will become clearer hereinafter, it is necessary to decrease this current flow in order to bring the milliammeter 12 to a zero reading. The method selected for decreasing this flow of current was to increase the resistance in the cathode circuit of tube 16 by adjustment of the variable resistances shown at 18, 18. This increase will result in a larger IR drop across the resistances 18, 18. As a result, the cathode of tube 16 becomes more positive. It follows that less current flows in the anode-cathode circuit of tube 16 so that current flowing across the resistance 17 to the point 20 is decreased. There are other ways in which this current could be decreased. However, it was not found to be feasible to control the value of the resistance 17, since in the arrangement employed the resistance was located so far from the control panel that high impedance at point 40 would cause noise "pick up." This is especially true where the pre-amplifier is separated by cable and is at some distance from amplifier 26.

Decreasing the current flowing past point 20 serves to bring the milliammeter 12 back to zero in the following way: As the current flowing across the tube 16 decreases, the potential of point 20 rises and becomes more positive. This takes place because the voltage drop across the resistance 17 is decreased, while the "high" side 40 is held at a fixed voltage by the line 41, since the point 42 is maintained at a constant regulated voltage. As a result, the grid 21 of the amplifying tube 22 becomes more positive. This increases the flow of current across the tube 22 and therefore increases the flow of current through the resistance 23. Since the high side of this resistance is also tied to the line 41 and is therefore maintained at a fixed potential, the point 24 becomes less positive or more negative. As a result, the grid 25 of the tube 26, biased by E. M. F. source 66, becomes more negative, thus decreasing the current flowing across the tube 26. This makes the point 27 more positive for reasons similar to those given in explanation of the increase in positive charge at point 20. As a result, an increase in positive potential appears on the grid 28 of the tube 29. It may be remarked that the tubes 22 and 26 greatly amplify the value of the voltage introduced at their grids 21 and 25 respectively, and tube 16 has some amplifying effect. At any rate, the net result of the operation of these tubes is to produce a voltage change

at the grid 28 which is approximately 20,000 times the voltage change at the grid 15. Thus by decreasing the flow of current across the tube 16 through adjustment of resistances 18, 18 a relatively large increase may be effected in the value of the voltage at the grid 28. The increase in voltage value at the grid 28 immediately causes an increase in the flow of current across the tube 29. This takes place because the plate of the tube 29 is tied to the fixed voltage line 41. The flow of current across the tube 29 opposes the flow of current in the circuit including resistor 38. By properly adjusting the variable resistances 18, 18 the flow of current may be reduced to zero or at least balanced to such an extent that the milliammeter 12 will not indicate any reading. At this adjustment the apparatus is ready to be operated to indicate very small current flow from the spectrometer collector plate 13.

Assuming that the spectrometer is in operation so that the aforementioned small current flows from collector plate 13, this current will flow along the line 14 through the input resistance 31 and from the plate 13 which is positively charged by the positive ions collected upon it. Ordinarily this flow of current is very small so that despite the large size of the resistor 31, the potential drop across it is also relatively small, the range being from 1 millivolt to 20 volts. This means that the current flowing is of the order of 1.25×10^{-14} to 2.5×10^{-10} amperes. However, the voltage from the point 32 to ground, is from substantially zero (ground voltage) with no ion current flowing, to +.001 maximum voltage. This occurs because of the operation of the negative feedback system. As pointed out hereinbefore the voltage value at the grid 15 and therefore at the point 32 with respect to ground is multiplied by about 20,000 times at the grid 28. This means that if the voltage value at the point 32 attempts to rise, this voltage value is multiplied by 20,000 times at the grid 28. The construction of the tube 29 is such that the voltage value at its grid is reflected in its cathode. Thus a voltage rise at the point 32 would establish an amplified voltage drop across the resistor 30 to the ground. This means that there is also an amplified voltage drop from the point 11 to the ground. Since the point 11 is directly tied by the line 14 to resistor 31, it follows that any attempt at an increased voltage at the point 32 is amplified and immediately fed back to the other side of the resistor through line 14. The feedback is opposite in phase, that is, a change in positive charge at 32 or 15 is fed back through line 14 as a negative charge and 20,000 times larger in value. The current flowing across the resistor 31 is collected by the mass spectrometer plate 13. Also, the voltage value at the line 14 must be 20,000 times greater than the value at the point 32. This means, for present purposes, that the point 32 possesses practically zero or ground voltage since the voltage drop across resistor 31 does not exceed 20 volts with maximum signal current. Naturally if the value at the point 32 were actually zero, the amplifying system would not work. It is approximately $\frac{1}{20,001}$ of the signal voltage developed across resistor 31.

Because of the aforementioned characteristic of the apparatus to maintain the point 32 substantially at ground voltage, changes in voltage drop across the resistor 31 are reflected as changes in the voltage value at the line 14. This means that the voltage drop at the point 32 from line 14 is substantially the same as the voltage

drop from the point 11 to the ground. Such being the case, while there is any current flowing in the line 14, there must be a voltage drop from the point 11 to the ground. Since the milliammeter 12 is connected in this circuit, it will indicate the voltage drop from the point 11 to the ground and therefore will vary linearly with voltage drop across the resistor 31. Voltage drop across the resistor 31 is caused by the current flowing in the line 14 from spectrometer collector plate 13. Accordingly the readings on the milliammeter 12 vary linearly with the current flowing from the spectrometer plate 13 and serve as a measure of such current.

As indicated hereinbefore it is necessary to provide a fixed voltage at the line 41 from power source 48, referred to in more detail hereinafter, in order to provide for proper operation of the apparatus. This voltage regulation is obtained by operation of the tubes 43, 43, and 44. Regulation is effected at the point 42 and the voltage delivered has been fixed at 135 volts. If this voltage tries to increase, more current will flow and the grid 45 of the tube 44 biased by E. M. F. source 67 will become more positively or less negatively charged. This means that more current will flow across tube 44 between cathode and plate. As a result, the grids 46, 46 of the tubes 43, 43 will become more negatively charged and cut down the current flowing across the tubes 43, 43. It will be noted that the current reaching point 42 flows across these tubes since it flows from point 76 which is B+, along the line 47, and through the tubes 43, 43 to point 42. Accordingly the tube 44 operates as a sensitive amplifier so that any slight change in potential at the point 42 is instantaneously reflected in an inverse manner to increase or decrease the flow of current through the tubes 43, 43 and maintain the current flow constant at the point 42, and therefore to provide constant voltage at that point.

The power supply to the line 47 is provided by a conventional rectifying circuit indicated generally at 48 and employing a typical power transformer and a double wave rectifier tube in a center tap arrangement. The purpose of this rectifying device is simply to supply the system from an A. C. source and to change the alternating current into direct current supplied at 76 which acts as the high voltage point. As indicated current flows through tubes 43, 43 to point 42 and from this point through the various tubes 16, 22, 26, and 29 to ground as at 68 and 69, returning through ground 70 to the center tap of the secondary of the power transformer of the power supply.

The portion of the circuit, including tubes 53, 55, comprises a safety device for preventing the voltage at point 42 from becoming dangerously excessive for tubes 16, 22, 26, 44 and 55 during the warmup period or due to breaks in the filament circuit.

It will be noted that the tubes 43, 43 which supply the current are connected in parallel and are heated directly from the power transformer winding 50 whereas the other tubes are heated from a rectified current provided at the point 42. Accordingly if the tubes 43, 43 are energized first, it is possible that an excessive amount of current would be fed through the tubes to the point 42 before the control tube 44 heated up. This might injure or burn out the filaments of all the tubes except the tubes 43, 43. Further-

more, it will be seen that the filaments of the tubes 16, 22, 26, 29, 44 and 55 are all connected in series, and if the filament in one of these tubes burns out or the current to the tubes is otherwise cut off accidentally as by pulling a cable plug, it is possible that a voltage surge to the filaments of the remaining tubes might take place. This could ruin the other tubes by causing filament to cathode breakdown.

The tubes are protected from these exigencies by means of a safety device. This safety device, generally designated 51, operates as follows: Before the control tube 44 warms up, the neon tube 53 acts to connect point 54 to the grids 46, 46. This applies a predetermined fixed voltage to the grids 46, 46 and prevents an excessive flow of current through the tubes 43, 43. As the control tube 44 warms up so does the tube 55, and as the tube 55 gets warmer and warmer the point 56 becomes more and more positive due to the flow of current across the tube 55 between anode and cathode. As the point 56 becomes more and more positive the potential drop between the points 57 and 58 decreases. Finally this potential decreases to such an extent that the neon tube 53 will cut out, since this tube responds to some specific threshold potential across it for operation. However, this tube will not cut out until the tube 44 is warmed up, because the filaments of the tubes 55 and 44 are connected in series. Accordingly no excessive amount of current can flow to the filaments in the amplifying system until the control tube 44 is in operation. Should, through accident or inadvertence, an excessive voltage appear at points 76 and 42 and consequently at grids 46, 46, there will be a large potential drop between the points 57 and 58 which will place the safety device in operation again. This may save many tubes from being burned out accidentally through improper operation of the amplifier or through accident. In order to maintain a uniform potential on the anode of tube 55 voltage regulator tubes 71, 71 are provided.

Concerning the operation of the resistance 60 connected in series with the meter 12, the numbers on Fig. 3 are multiplying factors; that is, the reading on the meter is multiplied by the number indicated to give the actual voltage difference. This is necessary since the currents flowing to the plate 13 may vary considerably, that is, by a factor of 1000 or more. Accordingly, the use of the resistances with the meter permits a single instrument to cover the necessary wide range.

Further it will be understood that filter 72, test jack 73, shunt resistors such as 74, 75 associated with the heater filaments, load resistors and many other items of conventional equipment are employed in a conventional manner in this system, and have not, therefore, been described in great detail.

Having thus described my invention, I claim:

1. An amplifying system of the character described comprising an amplifier including a series of direct coupled electric discharge devices having their heater elements connected in series, a power source for supplying a common potential to the elements of the discharge devices of said amplifier, means for maintaining the potential of the source at the amplifier at substantially a uniform level, said means including an electric discharge device interposed between the power source and the amplifier for the passage of current, means responsive to

changes in supply potential for controlling the current flow to the amplifier, and means responsive to overload conditions for limiting the passage of current through said last named discharge device.

2. An amplifying system of the character described comprising an amplifier including a series of electric discharge devices connected in cascade and having their heater elements connected in series, a power source to supply a common potential to the electric discharge devices of the amplifier, means for maintaining the potential of the amplifier at substantially a uniform magnitude, said means including at least one electric discharge device interposed between the power source and amplifier for the passage of current, an additional electric discharge device responsive to changes in potential of the power source for altering the conductivity of said first electric discharge device, and means for limiting the conductance of the electric discharge device of said current passage means during periods of overload.

3. An amplifying system of the character described comprising an amplifier having a series of electric discharge devices connected in cascade and having their heater elements connected in series, a source of electric power for supplying a common potential to the elements of the devices of the amplifiers, and means for coupling said power source to said amplifier, said means including an electric discharge device having its anode-cathode circuit interposed between the source and the amplifier, and an additional electric discharge device responsive to changes in potential delivered by said source to the amplifier for altering the conductivity of said first named electric discharge device for maintaining the potential at said amplifier substantially constant, said additional discharge device having its heater element in series with the heater elements of said series of electric discharge devices, and means for limiting the flow of current through said first named discharge device during the warm-up period of said series of discharge devices and said additional discharge device.

4. An amplifying system of the character described comprising an amplifier including a plurality of electric discharge devices terminating in a cathode follower and having their heater elements connected in series, a degenerative feedback circuit for the amplifier and current responsive means in the output thereof, a source of electric power for providing a common potential for energizing the elements of the devices of the amplifier, means for coupling the source to the amplifier, said means being responsive to changes in the potential delivered to the amplifiers for altering the impedance once and maintaining the voltage level substantially constant, and means responsive to overload conditions for limiting the changes in impedance of said coupling means.

5. An amplifying system of the character described comprising an amplifier including a plurality of electric discharge devices terminating in a cathode follower and having their heater elements connected in series, a degenerative feedback circuit for the amplifier and current measuring means in the output thereof, a source of electric power for providing a common potential to energize the elements of the discharge devices of the amplifier, and means for coupling the source to the amplifier, said means including an electric discharge device having its anode-

cathode circuit interposed between the source and the amplifier, means responsive to changes in potential at the amplifier for altering the conductance of said electric discharge device to maintain the potential level substantially constant, and means responsive to a predetermined overload potential for limiting the conductance of said coupling means.

6. An amplifying system of the character described comprising an amplifier including a plurality of electric discharge devices terminating in a cathode follower and having their heater elements connected in series, a degenerative feedback circuit for the amplifier and current measuring means in the output thereof, a source of electric power for providing a common potential to energize the elements of the discharge devices of the amplifier, and means for coupling the source to the amplifier, said means including an electric discharge device having its anode-cathode circuit interposed between the source and the amplifier, an additional discharge device responsive to changes in the common potential at the amplifier for altering the conductance of said first electric discharge device to maintain the potential substantially constant, and means bridged across said additional discharge device and responsive to overload potentials thereacross for limiting the conductance of said conducting means.

7. An amplifying system of the character described comprising an amplifier including a plurality of electric discharge devices having their filaments connected in series, a source of electrical energy for supplying a common potential to energize the elements of said devices, means for coupling said power source to said amplifier, said means including an electric discharge device having its anode-cathode circuit interposed between the power source and the amplifier, said device having an input circuit responsive to changes in potential delivered to the amplifier for altering its conductivity to regulate said po-

tential, and means coupled to said input circuit and responsive to potentials above a predetermined value for limiting the operation of said discharge device and prevent imposition of excessive potentials on said amplifier.

8. An amplifying system of the character described comprising an amplifier including a plurality of electric discharge devices having their filaments connected in series, a source of electrical energy for supplying a common potential to energize the elements of said devices, means for coupling said power source to said amplifier, said means including an electric discharge device having its anode-cathode circuit interposed between the source and the amplifier, an additional electric discharge device responsive to changes in potential at the amplifier for regulating the conductance of said first named electric discharge device to maintain the potential at the amplifier at a substantially constant level, and space discharge means bridged across the output of said second discharge device and responsive to the operation thereof for limiting the operation of the coupling means.
